UNITED STATES PATENT OFFICE.

JOHN GRIMSHAW, OF PATERSON, NEW JERSEY.

DESIGN FOR A HANDKERCHIEF.

SPECIFICATION forming part of Design No. 11,751, dated April 27, 1880.

Application filed February 7, 1880. Term of patent 3½ years.

To all whom it may concern:

Be it known that I, JOHN GRIMSHAW, of Paterson, in the county of Passaic and State of New Jersey, have invented a new and original Design for a Handkerchief, of which the following is a specification.

This invention relates, first, to the new ornamentation of the body of a handerchief; and, second, to the new ornamentation of the border of the same.

The accompanying photograph illustrates my new design.

The body A of the handkerchief contains a series of parallel stripes, *a b*. Over the lines *a b* are laid branches of serrated leaves *d d'*, in parallel lines, but so arranged that the branches *d* point in the direction of a diagonal line joining two of the corners of the handkerchief, and the branches *d'* point in the direction of a diagonal line joining the other corners. Between each of the branches *d d'* and *d' d* are small twigs, branches, or sprays of oval leaves *c*. The border B at the sides is formed of interlaced diagonally-crossed lines *f f'*; but at the corners the border is formed of diagonal lines *g* alone.

I claim—

1. The design for the body of a handkerchief, consisting of a background showing prominent parallel lines *a b* and of superposed branches *d d'*, substantially as described, and shown in the accompanying illustration.

2. The design for the body of a handkerchief, consisting of the parallel lines *a b* and branches *d d' e*, substantially as described, and shown in the accompanying illustration.

3. The design for the border of a handkerchief, consisting of the interlaced diagonally-crossed lines *f f'* and diagonal lines *g*, substantially as described, and shown in the accompanying illustration.

4. The design for a handkerchief, consisting of the body A, containing the parallel lines *a b*, branches *d d' e*, and border B, composed of interlaced diagonally-crossed lines *f f'* and diagonal lines *g*, substantially as described, and shown in the accompanying illustration.

JOHN GRIMSHAW.
